JAMES R. O'CONNELL, OF ELMIRA, NEW YORK, ASSIGNOR TO MORRISON MACHINE PRODUCTS, INC., OF ELMIRA, NEW YORK

FEED FINGER FOR MACHINE TOOLS

Application filed April 13, 1927. Serial No. 183,311.

This invention relates to feed fingers of the kind which are used for feeding work, such as rods or bars, on an automatic screw machine or the like.

5 Feed fingers as heretofore made generally consist of a piece of tubular material having one end shaped to fit the work which is to be fed and to grip the same, and the other end formed to engage with a feed mechanism. 10 The end of the feed finger which grips the work is hardened and one or more slots extend from this end toward the other end of the feed finger, the intermediate portion of the feed finger being given a spring temper 15 so that the slotted end or jaw of the feed finger will yieldingly grip the work. These feed fingers, even if very carefully made, have a tendency to break at the innermost end of the slot, since whenever the jaws of 20 the gripping portion of the feed fingers move toward or from each other, the greatest deflection or movement of particles of the material relatively to each other takes place at the innermost ends of the slot, thus resulting 25 ultimately in crystallization and in breaking of the feed finger at this point.

It has also been attempted to make feed fingers in which the slot or slots are provided with enlargements formed in such a manner 30 that the deflection of the material of the feed finger will be distributed uniformly over a considerable length of the feed finger. These enlargements of the slots must be of a definite curve and must be extremely accurately formed in order to insure a uniform distribution 35 of the deflection or movement of particles of the material throughout the length of the enlargement, and are consequently expensive to make. Furthermore very slight 40 variations in the heat treatment of the feed finger, or in the composition or dimensions of the material of the feed finger results in rendering the contour or curvature of the enlargements incorrect for a particular feed finger so that a uniform distribution of the deflection of the material is not attained.

The objects of this invention are to provide 45 a feed finger of comparatively inexpensive construction in which the deflection of the material takes place at a plurality of

points rather than at a single point or along a definite length of the feed finger, so that the tendency of these feed fingers to crystallize and break at a particular point is very materially reduced; also to provide a feed finger 55 with a series of substantially circular holes arranged lengthwise thereof for the purpose of distributing the deflection of the material of the feed finger to a series of points corresponding to the number of holes used; also to 60 provide a feed finger having apertures which are graduated to vary the tension with which the feed finger grips the work; also to improve the construction of feed fingers in other respects hereinafter specified. 65

In the accompanying drawings,

Fig. 1 is a central, longitudinal, sectional elevation of a feed finger embodying this invention.

Fig. 2 is an end view thereof. 70

Fig. 3 is a transverse, sectional elevation thereof on line 3—3, Fig. 1.

Fig. 4 is a longitudinal, sectional elevation of a feed finger of modified construction.

Fig. 5 is a longitudinal, central sectional 75 elevation of a feed finger of another modified construction.

The feed fingers shown in Figs. 1 to 5 inclusive are each provided with an end A of conventional form shaped to cooperate with 80 the work feeding or advancing mechanism of the machine, and obviously this end of the feed finger may be formed in any suitable or desired manner to cooperate with the particular machine for which the feed finger is 85 intended. B represents the work-gripping end of the feed finger, the inner surface b of which is shaped to conform with the contour of the outer surface of the work which is to 90 be fed. This end of the feed finger is provided with the usual slot or slots C extending inwardly from this end of the feed finger, one such slot being shown in the particular constructions illustrated, which divides the gripping end of the feed finger into two 95 spring jaws, but it will be understood that more slots may be employed, if desired, so that the feed finger may have three or more spring jaws. This work gripping end of the feed finger is heat treated in such a manner 100

as to produce the maximum degree of hardness, since this end of the finger is subjected to severe wear, for the reason that after the work has been advanced, the feed finger slides backwards along the work, while resiliently gripping the same, into a position to again advance the work. D represents the intermediate portion of the feed finger which must be heat treated in such a manner as to have a spring temper tending to press the parts of the work gripping portion B into engagement with the work. Because of the fact that the feed finger is cylindrical in cross section, it will be obvious that portions of the feed finger which are separated by the longitudinal slot or slots C will, because of their curved form, offer much greater resistance to bending than would flat spring plates of the same cross sectional area and consequently when slots of uniform thickness are used, the greater part of the deflection of the metal caused by the movement of the gripping portions B toward and from each other, will take place at the innermost end of the slot and consequently cause crystallization and breaking at these points, as has been pointed out.

In order to relieve the stresses and deflection in the material at the innermost end of the slot a plurality of holes are drilled in the spring tempered portion D of the feed finger at points intersecting the slot C, three such holes E being provided in the construction shown in Figs. 1 to 4. These holes form rounded recesses in the opposite edge portions of the spring jaws and can be readily formed by the ordinary drilling operation, and therefore add practically nothing to the cost of the feed fingers. These holes or recesses in the edge portions of the spring jaws, by reducing the cross section of the spring tempered material of the part D of the feed finger, cause the deflection of the material of the feed finger to take place at the portions of the feed finger adjacent to these holes and consequently the total deflection in the material of the feed finger is distributed at a number of points corresponding to the number of holes, thus greatly reducing the deflection of the material at any part of the feed finger and thus greatly reducing the tendency of the finger to break. Consequently in the construction shown in Figs. 1 and 4, when three holes or enlargements are used in the slot C, the total deflection in the material of the feed finger will take place approximately in three planes extending transversely of the feed finger and through the centers of the holes, the greatest deflection taking place in the plane passing through the hole farthest removed from the work gripping portion B of the feed finger, a lesser deflection taking place in the plane extending through the middle holes or enlargements, and a still smaller deflection at the hole or enlargement

nearest to the gripping end B of the feed finger. If more than three holes are used a further distribution of the deflection takes place, and if only two holes are used the deflection is divided between the transverse planes passing through the two holes.

In the particular construction shown in Figs. 1 to 3, a second series of holes F is employed, which holes extend through the feed finger in a longitudinal plane substantially at right angles to the slot C, and these holes further reduce the cross section of the material of the feed finger and enable the feed finger to yield more readily in the transverse plane extending through the holes or enlargements E and F. The holes F may be arranged substantially in the same transverse planes as the holes E as shown in Figs. 1 and 3, or, if desired, they may be staggered with reference to the holes E.

In the particular construction shown in Fig. 5 an arrangement of holes is illustrated which tends to equalize the deflection of the material at different points along the slot C. Since the maximum deflection of material will tend to take place at the portions of the feed finger adjacent to the innermost end of the slot, if the slot is of substantially uniform width, an equalization of the distribution of the deflection in the material can be effected by providing a hole or enlargement of comparatively small diameter at the portion of the slot C farthest removed from the gripping portion B of the feed finger, and by making the other holes or enlargements of successively greater diameter. In the particular construction illustrated in Fig. 5 three holes or enlargements are used in the slots C, the hole G at the innermost end of the slot being of comparatively small diameter, the intermediate hole H being of somewhat greater diameter and the hole I being the largest in diameter. By means of this arrangement the deflection of the material of the feed finger in planes extending transversely through the centers of these holes can be made equal in the transverse planes extending through each of these holes, so that in the particular construction shown approximately one-third of the total deflection of the material takes place in each transverse plane extending through a hole. The remaining portions of the parts D of the feed finger may be imperforate, or if desired a series of holes may be provided in a longitudinal plane of the feed finger approximately at right angles to the plane of the slot C and these holes may be all of the same size or of different sizes and may be arranged in transverse alinement with the holes G, H, and I or staggered therewith. In the construction shown in Fig. 5, three holes K, L, and M are used which are successively of increased diameter and thus cooperate with the holes G, H and I in reducing the transverse

cross sectional area of the feed finger at these holes and thus render the parts of the feed finger more resilient. It will be obvious that the same result could be accomplished if the holes G, H and I shown in Fig. 5 were made of the same size and the holes K, L and M successively larger in size as shown, since the deflection of the material in each case takes place at the reduced cross sectional area of the resilient portion D of the feed finger, and by making the greatest reduction in cross sectional area at points nearest to the gripping portion B of the feed finger, an equalization of the distribution of the deflections of the material in the feed finger may be accomplished.

By making the transverse holes in the spring portion D of the feed finger substantially circular in cross section it will be obvious that not only is the cost of making these holes very inexpensive because of the simplicity of the drilling operation, but also the round holes leave no sharp corners or angles in the feed finger at which the deflection of the material may be concentrated and thus cause a rapid crystallization of the material. Furthermore by reducing the cross section of the feed finger at a plurality of definite points as shown in the drawings, an inaccuracy in the heat treatment, such, for example, as would render a portion of the intermediate parts D of the feed finger harder than is required to produce the desired spring action, would not damage the feed finger, since even if the deflection of the material is entirely prevented at the hole nearest to the gripping portion B, the other two holes will still cause a distribution of the total deflection, which will result in increasing the life of the feed finger.

I claim as my invention:—

1. A work advancing feed finger for a machine tool having a hardened work gripping end, a spring portion adjacent thereto and located at a distance from said end and a slot extending lengthwise of the feed finger from the work gripping end through the spring portion thereof, said slot having a plurality of enlargements in said spring portion of the feed finger, which reduce the cross sectional area of the spring finger at the enlargements in said slot.

2. A work advancing feed finger for a machine tool having a hardened work gripping end, a spring portion adjacent thereto and located at a distance from said end and a slot extending lengthwise of the feed finger from the work gripping end through the spring portion thereof, said slot having a plurality of rounded enlargements located in said spring portion and which form portions of reduced cross sectional area in the spring portion of said feed finger, to which portions is distributed the total deflection of the material in the spring finger, caused by the

movement of the work gripping parts toward and from each other.

3. A work advancing feed finger for machine tools having a hardened work gripping end and a spring portion adjacent thereto, said work gripping end and spring portion being slotted to divide the same into a plurality of resilient work gripping jaws, and a plurality of substantially circular holes in the spring portion of said feed finger which decrease the cross section of said spring portion to distribute the deflection of the material due to flexing of said spring portion to the parts of the feed finger adjacent to said holes.

4. A feed finger for machine tools having a hardened work gripping end and a spring portion connected therewith and located at a distance therefrom, said work gripping and spring portions being slotted to divide the same into a plurality of spring members and said spring portion having a plurality of drilled holes therein at intervals lengthwise thereof, to reduce the cross section thereof at intervals.

5. A work advancing feed finger of substantially tubular form for machine tools, one end of which feed finger is divided into a plurality of spring jaws having spring portions terminating in work gripping ends, the cross sectional area of the spring portions of said spring jaws being reduced in cross section at intervals along the length thereof and at a distance from said gripping ends to provide for a distribution of deflection of the material at intervals along said spring portions, when the spring jaws are flexed, to each of the portions of reduced cross sectional area.

6. A work advancing feed finger of substantially tubular form for machine tools, one end of which feed finger is divided into a plurality of spring jaws having spring portions terminating in work gripping ends, said spring jaws being provided at their edge portions with inwardly extending recesses and being provided with orifices intermediate of the edge portions thereof and at a distance from said work gripping ends, said recesses and orifices reducing the cross sectional area of said spring jaws at intervals along the length thereof to distribute the deflection of the material of said jaws, due to flexing of said jaws, to said reduced cross sectional areas.

7. A work advancing feed finger of substantially tubular form for machine tools, said finger being slotted lengthwise to divide a part of the same into a plurality of spring jaws each of which has a spring portion terminating in a work gripping end, the material of said jaws being of reduced cross sectional area at a number of points lengthwise thereof, said reduction in cross sectional area being greatest at portions of said jaws adja-

cent to said work gripping end and lesser at portions remote therefrom to provide for a distribution of the deflection of the material of said jaws, when the same are flexed, to all of said portions of reduced cross sectional area.

8. A work advancing feed finger for machine tools including a substantially tubular body portion divided lengthwise into a plurality of spring jaws each of which includes a spring portion terminating in a work gripping end, the spring portion of said spring jaw being provided with rounded recesses in the side edges thereof, said recesses being largest at the portions of the spring jaws adjacent to the work gripping ends thereof and being of gradually reduced size toward the other ends of said spring jaws, to provide portions of said jaws of varying reduced cross sectional area, said variation in cross sectional area serving to distribute deflections of the material in said spring jaws substantially equally throughout the portions thereof of reduced cross sectional area.

25 9. A work advancing feed finger for machine tools including a substantially tubular body portion divided lengthwise into a plurality of spring jaws each of which includes a spring portion terminating in a work gripping end, the spring portion of said spring jaw being provided with rounded recesses in the side edges thereof, said recesses being largest at the portions of the spring jaws adjacent to the work gripping ends thereof and being of gradually reduced size toward the other ends of said spring jaws, to provide portions of said jaws of varying reduced cross sectional area, said variation in cross sectional area serving to distribute deflections of the material in said spring jaws substantially equally throughout the portions thereof of reduced cross sectional area, and a series of holes in said jaws extending lengthwise thereof for producing a further reduction in the cross sectional area thereof.

10. A work advancing feed finger for machine tools including a substantially tubular body portion divided lengthwise into a plurality of spring jaws each of which includes a spring portion terminating in a work gripping end, the spring portion of said spring jaw being provided with rounded recesses in the side edges thereof, said recesses being largest at the portions of the spring jaws adjacent to the work gripping ends thereof and being of gradually reduced size toward the other ends of said spring jaws, to provide portions of said jaws of varying reduced cross sectional area, said variation in cross sectional area serving to distribute deflections of the material in said spring jaws substantially equally throughout the portions thereof of reduced cross sectional area, and a series of holes in said jaws of graduated size, the

largest holes being nearest to the work gripping end of said spring jaw to effect further graduated reduction at intervals in cross sectional area of said spring jaws.
